UNITED STATES PATENT OFFICE.

CARL KLAASSEN, OF WANDSBECK, GERMANY.

COMBINED FENDER AND NET FOR STREET-RAILWAY OR TRAMWAY CARS.

SPECIFICATION forming part of Letters Patent No. 687,318, dated November 26, 1901.

Application filed June 7, 1901. Serial No. 63,636. (No model.)

To all whom it may concern:

Be it known that I, CARL KLAASSEN, brick-layer, of No. 2 Wasserstieg, Wandsbeck, near Hamburg, German Empire, have invented 5 new and useful Improvements in a Combined Fender and Net for Street-Railway or Tramway Cars, of which the following is a statement.

The present invention relates to a safety 10 device for street-railway and tramway cars; and it consists of a fender attached and easily detached from the platform of the car and consisting of two beams placed at an acute angle to each other and provided with cushions and a net situated knee-high over the fender and rails.

The accompanying drawings illustrate the subject of the present application, Figure 1 being a side elevation, and Fig. 2 a plan view. 20 Attached to the platform 1 of the car is an angle-piece 2, to which in turn are vertically secured the flat bars 3, to the lower end of which the frame 5, provided with a roller 4, is attached. The frame is made more rigid by 25 the cross-bars 6. Fastened to the frame itself, which is constructed in the shape of a triangle with the apex directed toward the direction of travel, and in the center line of the car cushions or pads of elastic material are 30 arranged on the side bars 7. This part serves to push aside bodies lying on the track in front of the car. This part (the so-called

"fender") can also be adjusted in height. A frame 9, of rectangular shape, is also attached to the flat bars 3, and it is likewise fitted externally with a cushion 10 of elastic material or with a pneumatic cushion-strip. Inside this frame 9 rods 11 are attached at right angles to the direction of the car's travel, to which a net 12 is hung or secured. The frame 9 is 40 stiffened by the railing 13 and is secured knee-high above the surface of the ground, and, like the frame 5, it is adjustable in height.

Having now particularly described and ascertained the nature of this invention, what I 45 claim as new, and desire to secure by Letters Patent, is—

A safety device for street-railway cars consisting of a fender adjustable in height and situated in front of the car composed of a triangular frame and over which is a rectangular frame provided with a net and situated knee-high above the track, both being provided in front with cushion of elastic material, so that moving or stationary persons are 55 caught by the net while persons or bodies lying on the track are pushed aside by the fender.

In witness whereof I have hereunto set my hand in presence of two witnesses.

CARL KLAASSEN.
